UNITED STATES PATENT OFFICE.

JOHN MACKIE, OF WILLIMANTIC, CONNECTICUT, ASSIGNOR TO THE AMERICAN THREAD COMPANY, OF NEW YORK, N. Y., A CORPORATION OF NEW JERSEY.

WINDING-MACHINE.

1,071,248.

Specification of Letters Patent. Patented Aug. 26, 1913.

Application filed September 25, 1912. Serial No. 722,170.

To all whom it may concern:

Be it known that I, JOHN MACKIE, a subject of the King of Great Britain and Ireland, residing at Willimantic, Windham county, State of Connecticut, have invented certain new and useful Improvements in Winding-Machines, of which the following is a full, clear, and exact description.

My invention has reference to improvements in and relating to machines for winding thread, yarn, twine and the like, and comprises appliances to feed, wind and finish spools of thread and the like, and means whereby all the working parts of the machine are made to work automatically.

One of the principal objects of my invention is to provide means for automatically supplying spools to and removing them from the winding spindles.

Another object of my invention is to provide a new and improved means of drawing the finishing end of the thread beneath the last few turns of the winding.

Another object of my invention is to provide suitable means for clamping the spool to be wound upon the spindle and releasing it therefrom.

Other objects of my invention are to produce new and useful combinations of mechanisms for accomplishing results which contribute to the general object of the invention.

In performing the functions of the machine embodying my invention, spools are fed by hand from a trough or box in the rear of the machine into spool chutes, there being one chute for each winding spindle. The spools are moved through these chutes by conveyer belts until they reach the front part of the machine. They are here received upon transferring pins, which are mounted upon a tilting yoke or bar, which bar when tilted and moved upward transfers them into vertical chutes, where they are held by suitable detents. As a spool is transferred into a vertical chute, a spool is forced out of the upper end of that vertical chute onto one of a series of pins carried by a second tilting yoke, which tilting yoke, when it is moved, carries them to a third set of transfer pins, which move and carry the spools into spring jaws upon a transferring arm. This transferring arm then swings in the arc of a circle and places the spools upon the winding spindle. Each winding spindle is provided

50 with a clamping spindle, which is then actuated so as to hold the spool firmly to the spindle. The thread is then applied to the spool by an ordinary flier, the spindle being rotated slowly, as is usual in ball winding machines, so as to make the winding progress circumferentially. After the winding has been partially completed, the spindle is tilted downward, so that its axis makes a smaller angle with the axis of the flier, in order to lay on the outer layers of the wind 55 more obliquely, thereby lengthening and improving the finish of the spool. When the wind is substantially completed, the rotation of the flier and spindle are stopped and a finishing needle is brought in proximity to 60 the last wind of the thread. The flier and spindle are then further actuated, so that the flier makes two more turns, and the needle is then moved so that the thread upon a third additional turn of the flier falls into 65 the jaws of the needle. This third turn is then produced. In making this third turn, the thread is also brought into a thread-holding clamp which grips the thread, means being provided so that the 70 thread will be held in the path of a cutting blade. Thereupon, the cutting blade acts to sever the thread, and the needle is retracted, drawing the severed end of the thread beneath the last two turns of the winding, 75 thus finishing the product. Thereupon the spool-clamping devices are released and retracted, so that the wound spools fall into 80 a longitudinal trough containing a conveyer, which carries them to the discharge end of 85 the machine. Immediately the doffing is completed, an empty spool is placed on the spindle, the clamping spindle passed upward through the hole in the spool, clamping it to the spindle, and winding operation 90 repeated, the spindle frame returning to its initial position, and the thread clamp released after a few turns of the flier. This operation continues, the spools being automatically placed upon the spindle, wound 95 and removed therefrom so long as the spool chutes are supplied with spools.

The following is a description of an embodiment of my invention, reference being had to the accompanying drawings, in 100 which—

Figure 1 shows in perspective a partial front view of a machine embodying my invention. Fig. 2 shows a rear elevation of the right hand end of a machine embodying 110

my invention. Fig. 3 shows a right hand end elevation of the same. Fig. 4 shows a plan view of said right hand end. Fig. 5 is a transverse section showing certain details. Fig. 6 is a plan view showing the train of gearing between the pulley shaft and the barring shaft. Fig. 7 is a sectional view showing the train of gearing between the barring shaft and the main cam shaft. Fig. 8 shows in plan view, the main cam shaft. Fig. 9 shows the trains connecting the loose gear on the pulley shaft with the cam and barring shafts. Figs. 10, 10^a, 11, 12, 13, 14, 15, 16, 17 and 18 show various views of cams upon the main cam shaft. Fig. 19 shows means for feeding the spools and means for tilting the spindle carrying frame and other details. Fig. 19^a is a diagram of gears. Fig. 20 shows the spindle and flier, together with parts of the spool feeding mechanism and associated elements. Fig. 20^a shows a details of the yoke tilting lever and cam. Figs. 21 and 22 are detail views of the winding spindle and clamping spindle. Fig. 22^a is a section on the line α — α Fig. 21. Fig. 22^b is a vertical section of the lower end of Fig. 22. Fig. 23 is a detail view of the clamping and releasing mechanism and of the finishing needle and associated parts. Fig. 23^a is a detail of the needle carrying lever. Fig. 24 is a further detail view of the clamping and releasing mechanism. Figs. 25 and 26 are details of the thread clamp. Figs. 27 and 28 are plan and side elevations of the thread-cutting mechanism. Figs. 29 and 30 are detail views of the knife of the cutting mechanism. Fig. 31 is an enlarged view of the winding spindle, clamping spindle and certain associated parts, including part of the spool transferring mechanism. Figs. 32 and 33 are end and plan views of the spool placing arm for placing the spool upon the winding spindle. Fig. 34 shows means for returning the spool placing arms. Fig. 35 is a detail of a portion of the same, with parts in different positions. Figs. 36, 36^a and 36^b are detail views of a portion of the spool feeding mechanism, including a portion of the vertical feeding chutes. Figs. 37 and 37^a are details of the horizontal chutes and associated parts. Fig. 38 is a plan view of the belt shifters. Fig. 39 is a rear elevation of the belt shifter and parts for operating the same. Fig. 40 is a detail view of the trip for releasing the belt shifter and the cam for actuating the same. Fig. 41 is a diagrammatic view showing certain details.

60 Referring more particularly to the drawings, A is the gear section of the machine containing the larger portion of the cams and gearing.

B is the winding section in which the winding mechanism proper is located.

C is a moving frame carrying the spindles on which the winding is done, and shafting for operating certain finishing devices, this moving frame consisting of end pieces connected together by bars c' c' carrying 70 the spindles and associated parts, the same being mounted so as to have an axial movement around the axis 5 carried by the stationary frame.

In the machine for carrying out the operation above referred to, 1 is the main shaft running the length of both the gearing and winding sections, mounted in a suitable frame. This main shaft is connected by gearing 1^a, 1^b to 1¹ inclusive (Figs. 4 and 5), 75 to the driven or pulley shaft 2 having a pulley 2' fixed thereon. This pulley shaft has an idle pulley 2² and a loose pulley 3, which latter is connected to a barring shaft 4 by gearing 3^a, 3^b to 3¹ inclusive (Figs. 6 and 7), said 80 barring shaft being operated so as to make one complete revolution during every cycle of the machine. The gear 3^a is fast to the pulley 3. The gears 3^d and 3^e are fast to each other but loose on the shaft 2. The barring 85 shaft 4 is connected with a main cam-shaft 5 by gearing 5^a, 5^b, 5^c, 5^d and 5^e (Fig. 9), so that the main cam shaft 5 revolves synchronously with the barring shaft, making a single revolution in each cycle of the machine. The barring shaft acts to control the movement of the belt shifter (hereinafter referred to) in one direction, so that the barring shaft and cam shaft are operated intermittently and the main shaft, which controls 90 the movement of the belt shifter in the other direction, is operated alternately therewith during the normal periods of rest of the barring and main cam shafts. This is accomplished by the belt shifter cam 6 (Figs. 2, 6, 10^a 95 and 39), driven by the barring shaft through bevel gears 6^a, 6^b, and the trip operating cam on the main shaft hereinafter referred to. The cam 6 (Fig. 39), acts upon a weighted lever 7 carrying a pawl 8 adapted to engage a projection 9 on a belt shifting slide 10 mounted in suitable bearings, and embracing the belt 10'. This belt shifter 10^b slide 10 is provided with a spring 11 tending to move it toward the right (Figs. 2 and 39). The cam 6 is driven by the barring shaft through bevel gears, as shown in Fig. 7, and as it revolves moves the lever 7, as viewed in Figs. 2 and 39, to the right, the belt shifting slide being at that time retracted by its spring 11. Somewhat before the lever 7 reaches its extreme right hand position, Fig. 39, the pawl 8 drops down behind the projection 9. Thereupon, upon a continued movement of the cam 6, the high point of the cam 6 passing, the lever 7 is released thereby, so that it is thrown quickly 110 toward the left by reason of the weight 7', the pawl 8 hitting the projection 9 and moving the belt shifter slide with a quick mo- 115

tion toward the left (Figs. 2 and 39), so that the belt is forced on to the pulley 2' which is fast upon the pulley shaft. This results in disconnecting the barring and cam shafts from the source of power and in connecting the main shaft 1 with the source of power. The main shaft thereupon begins to revolve, and continues to revolve until a tripping cam 12 thereon engages the trip 10 13 (Figs. 2 and 40), moving the tripping rod 14, forcing upward the pawl 8 so that it no longer engages the projection 9 and permitting the spring 11 to move the belt shifting slide 10 with a quick movement 15 to the right, thus shifting the belt to the loose pulley 3 upon the pulley shaft 2, whereupon the main shaft 1 stops and the barring and cam shafts 4 and 5 begin to revolve. This movement of the main shaft 1 is slightly less than a complete revolution. There is, however, a time when both the cam and the main shafts are revolving, this being during a portion of the finishing period 20 during which time three extra winds are added, as hereafter described. This is brought about by the action of a cam 23 (Fig. 5) upon a lever 21, which is connected by a belt 20 to a drum 19^a in such a way that it will cause the pulley shaft 2, and with it 25 the main shaft 1, to revolve a sufficient distance to wind the three extra turns, in conjunction with the thread clamping, cutting and needle-moving elements. This additional movement of the main shaft completes 30 its revolution, being complementary to the partial revolution referred to in the last paragraph. The band 20 leading from this lever 21 has one end affixed to the drum 19^a, which drum is connected to a disk 17. This 35 disk carries a pawl 18 (Figs. 5 and 38), which pawl engages with a ratchet wheel 19 (Fig. 5) rigidly secured to the pulley shaft 2, the disk 17 and drum 19^a being loose thereon. As the barring shaft rotates, the 40 lever 21 is actuated so as to unwind its band and wind up the band 16 of the weight 15, causing the shaft 2 to revolve sufficiently to rotate the fliers three extra turns. As the cam 23 releases the lever 21, the weight 15 45 returns the disk 17 and pawl 18 to initial position, viz., to the position in which the pawl 18 is at the uppermost point of the disk 17. Over the pawl 18 lies a weight 24 (Figs. 2, 50 38, 39) fixed to a shaft 24^a and tending to fall by gravity. This weight, when it falls, engages a projection 25 on the detent 18 so as to retract the detent from the ratchet 19 against the action of the spring 18^a. When the belt shifter is in one position, the left 55 hand position (Fig. 39), the weight 24 retracts the detent 18 so as to prevent wear and clatter. When, however, the belt shifter moves in the other direction, the weight 24 is moved by the cam 24^b acting on the arm 60 24^c fast to shaft 24^a so as to release the pawl

18 and permit it to engage the ratchet 19 which, under the action of the cam 23, then revolves the disk 17 sufficiently to add the three additional winds and perform the other necessary finishing functions. 70

The ratchet wheel 19 is rigidly connected to the shaft 2, so that when it is revolved, it revolves that shaft also, and hence revolves the fliers 26 geared thereto by gears 26^a, 26^b (Fig. 20), there being one flier for each 75 spindle.

27 is a box containing unwound spools (Fig. 19). 28 is one of a series of primary spool chutes, there being one for each winding spindle. 29 is a conveyer belt in the bottom of one of said chutes (Figs. 19, 20), there being one belt for each chute. Each conveying belt passes over a sprocket wheel 80 30, which is driven by a belt 31 from the main shaft. At the discharge end of each 85 chute 28 is a stop consisting of two bars 28^a pivoted at 28^b and having pins 28^c (Figs. 37 and 37^a), which, because of the weight of the rear ends of the bars 28^a, are normally held in the path of the spools within 90 the chutes 28.

32 is a yoke having a series of pins 33, one for each primary chute, which yoke is actuated so as to turn about its axis 34 by the cam 35 on the main shaft 1 acting 95 through the lever 36 and connecting link 37, which acts upon a yoke tilting cradle 38 (Figs. 1, 20 and 20^a). When the yoke 32 is in horizontal position, it depresses the forward ends of the bars 28^a (Fig. 37^a) so 100 as to permit the spools to pass by the pins 28^c and to the pins 33.

39 is a cam on the main shaft acting through the weighted lever 40 (Fig. 19) to lift and to retract the yoke 32 from elevated position, the weight 41 coacting with the cam 39 to lift the yoke after it has been turned into vertical position by the link 37, so as to lift the spool into a vertical chute 42. 105

43 is a spring detent, there being one for 110 each chute, past which the spools are forced (Figs. 19 and 36^a), and which hold the spools from returning when once lifted by the yoke 32. At the upper end of the vertical chutes 42 is an oscillating rod 44 (Figs. 19 and 36) provided with pins 45, which receive the uppermost spools as they are forced out of the chutes by the entry of spools into each of the lower ends of the vertical chutes 42. This oscillating rod 44 115 is operated by crank arm 46 through a connecting rod 47, which is connected to a lever 48, pivoted in the frame at 48', the same being operated by a lever 49 connected thereto by a link 50, the lever 49 itself being actuated by a cam 51 on the main shaft, (Figs. 36, 36^b). 120

52 is a pin mounted upon a slide 53 (Figs. 20 and 31), there being one slide for each vertical chute, adapted to receive spools 13^a

from the pins 45. This slide 53 is moved toward the rear of the machine by a lever 54 connected thereto by the link 54^a actuated by the rock-shaft 55, which in turn is actuated by the cam 56 on the cam shaft 5 (Figs. 8 and 12) engaging the lever 55^a to move the pin 52 with its spool between the jaws 57 of a spring clamp mounted upon the arm 58 carried by the oscillating rod 59. One of the jaws is pivoted at 57^a and forced toward clamping position by a spring 57^b. The arms 58, carried by the rod or shaft 59, are actuated by a sector 60 (Fig. 20) engaging a gear 61 thereon, so as to make substantially a one-half revolution, the several arms carrying the spools to the winding spindles 116, there being one winding spindle for each vertical chute. The sector 60 is operated by cam 60' (Figs. 8 and 11), acting on a pin 60^a on a lever 60^b, which is loosely mounted on shaft 55. The outer end of this lever is connected by a link to the rock-arm 60^c, which is connected to the shaft of the sector. In order to have the placing arms 58 return quickly to initial position, the rock-shaft 59 is provided with an arm 63 (Fig. 34), which holds the placing arms in actuated position until the spool is clamped upon the spindle 116. This holding action is due to a detent 64 upon a lever 65. To the rear end of this lever is connected a link 66, which is connected to a weighted lever 67 pivoted at 68, the right hand end of which is acted upon by a cam 69 on the barring shaft. When this cam reaches its high point, its surface falls abruptly so as to permit the weighted lever 67 to fall quickly, giving the rear end of the lever 65 a very quick downward motion. The front end of this lever is provided with a pin 70, which, when the arm 63 is in held position, as shown in Fig. 35 lies some distance beneath that arm. Upon release of the lever 67, and the consequent upward throw of the front end of the lever 65, detent 64, is released. The pin 70, at this instant strikes the lower surface of the arm a quick blow, causing it to be thrown back very quickly so as to quickly retract the placing arms 58, from the winding spindles 116. Upon the shaft 59 is a pulley 72 on which is a belt 72 passing around a pulley 73 on the main shaft 1, which is revolving at this time (Fig. 34). This belt 55 slips upon the pulley 71 so as not to seriously interfere with its quick backward throw, and serves to carry the shaft 59 with its arm 63 and spring clamp arms 58 back to its proper initial position, after the force 60 of the quick backward throw is exhausted. This quick "get-away" action materially increases the speed of the machine. The cam operating the lever 67 to release it is so timed that this release and the quick "get-away" action of the clamping arms 58 takes

place as soon as the spools are clamped upon the winding spindles 116.

In order to prevent any substantial interference of the belt 72 with the quick "get-away" action, I provide tightening pulleys 72^a carried by a lever 72^b pivoted to the frame at 72^c and having a depending arm 72^d. This arm is engaged by the lever 67 when it is raised, so as to move the pulleys 72^a to loosening position. As the lever 68 falls, the pulleys 72^a move so as to tighten the belt 72. The arm 63 has, however, been given the quick "get-away" start before the belt 72 fully tightens.

The spindle 116 itself (Figs. 20-22) is mounted in a bearing 74 (Figs. 20-22), which is carried by bars c' c' in the tilting frame. The angle gear 75 is fixed to the spindle 116 between the bars c' c' carried by the tilting frame. The gear 75 is driven by a gear 75^a on the shaft 75^b, which is driven by gearing 75^c from the shaft 2 (Fig. 19^a).

In order to securely clamp the spool upon a winding spindle, I make the winding spindle 116 hollow and pass through it centrally a hollow clamping spindle 62. This clamping spindle is provided with a hooked rod 76, running through it and revolute relatively thereto on an axis eccentric with the axis of the clamping spindle 62. This rod 76, at its uppermost end has a hook 77, which in one position lies in a notch in the end of the clamping spindle 62, and in the other position, Fig. 22, 100 extends beyond the clamping spindle so as to engage a spool thereon. Its lower end abuts against a stop 78 and in proximity thereto has secured to it a pinion 79 adapted to engage and disengage a rack. After the spools have been placed upon the spindles 116, the stop is raised by the lever arms 81-81^a carried by the shaft 82, the former of which is actuated by the cam 83 (Figs. 8 and 18), being held in engagement therewith by a weight 81', the arm 81^a acting on the collar 114 to which the stop 78 is connected. This raises the clamping spindle 62 with its rod 76 and its hook 77 through the hole in the spool, and also brings the gear 79 into engagement with its rack 80. This rack 80 is then given a short movement by the cam 84 (Figs. 8, 10 and 10^a) acting on lever 84^a pivoted at 84^b, sufficient to revolve the gear substantially a half revolution and changing the hook 77 from non-holding position to holding position, or vice versa. After the hook is turned to clamping position, the stop 78 is moved downward so as to permit the hook 77 to engage and hold the spool, and to permit the gear 79 to disengage its rack 80. After the parts have assumed this position, the belt 10' is shifted by the action of the cam 6 upon the barring shaft and weight 7', so as 130

to directly drive the pulley shaft 2, with the result that the fliers 26 which are geared thereto, together with the main shaft 1 and the spindles 116 through the gearing 75^b and 75^c, are caused to revolve in the proper directions. The winding continues for a time, after which the cams 85 upon the main shaft, acting through connections 85^a, 85^b, 85^c, 85^d (Fig. 19), tilt the spindle-carrying frame for the final windings. The cam 12 upon the main shaft then operates the trip 13 so as to release the belt shifter 10 and shift the belt 10' on the pulley 3 so as to revolve the barring shaft 4 and main cam shaft 5. As the main cam shaft 5 revolves under this action the cam 86 (Figs. 8 and 15) acting upon an arm 87 on the rod 88, moves the forward end of the lever 89 (Fig. 23) downward through the connections 88^a 20 and 88^b. This lever is provided with a stud 90, which moves in a slot 91, having a switching piece 92. It also has a slot 93 which enables it to have a longitudinal motion. The downward movement of the outer end of the lever 89 forces that lever, together with the needle, slightly toward the rear of the machine, and brings the needle 94 in proximity to the wound ball, where it remains until the pin 90 reaches the middle of its downward movement in the slot 91. When the needle 94 is in this position, the cam 23 acts to unwind the band 20, and the pawl 18 engaging with the ratchet wheel 19 moves the pulley shaft 2 enough to make three additional turns of the flier 26. After two turns have been made, the front end of the lever 89 is forced by the cam 86 to the bottom of the slot 91, drawing the needle 94 a little forward and also raising it so that the opening between its jaws lies in the path of the thread upon the third additional turn of the flier so as to receive the thread. The cam 86 then operates the shaft 88 so as to 40 raise the outer end of the lever 89, depressing the needle 94 so as to draw it and the end of the thread, severed as below described, beneath the last two winds, the needle and lever being given at that time a slight forward motion due to the switch plate 92 which engages the pin 90 upon the lever 89. The spring 89^a tends to retract the lever 89 so as to cause the pin 90 on its upward movement past the switch plate 92 50 to move in front of said switch plate. This switch plate is weighted by a weight 95 so as to stand normally in switching position, being carried by and pivoted to a fixed arm 96, the result being that on the upward stroke of the pin 90, the switch plate guides the same into the front portion of the slot 91, while upon the downward stroke thereof it guides the pin into the rear portion of the slot.

The thread, as it passes into the jaws of

the needle 94 on the third auxiliary turn, also passes between the jaws of a clamp 97, which just prior to that time has been opened by the action of the cam 98 (Figs. 8 and 13) upon the arm 99 attached to the rock-shaft 100 carrying the rock-arm 101. This clamp (Figs. 23 and 24) consists of a rod 102 passing through a hollow bar 103 and terminating in a head 104, which head carries a wire 105. A spring 106 normally tends to keep the head 104 in engagement with the end of the hollow rod 103. The lever 101 actuated by the cam 98 engages the end of the rod 102 carrying the head 104 and forces it rearward, as shown in dotted lines (Fig. 24) just prior to the third auxiliary wind, and as the third auxiliary wind is completed, releases it so as to clamp the thread in the clamp, the front side of the wire 105 engaging the thread between the clamp and the wound portion. When the parts are in this position, the lever 107 connected to the rock-shaft 108 actuated by the arm 109 and cam 110 (Figs. 8 and 14) actuates a plunger 111 carrying a head 112 having a knife 113 (Figs. 27-30), which knife, when the plunger is actuated, engages the thread near to the clamp 97 and between the clamp 97 and the wire 105 so as to sever the same, after which the knife is retracted. After severing the thread, the needle 94 is retracted as above described, for the purpose of drawing the severed end beneath the last two turns which were wound from the shank of the needle. As soon as the end of the thread has been drawn under the last two turns, so as to finish the wind, the stop 78 is raised, carrying with it hook 77 and gear wheel 79, which engages the rack 80. The rack is then moved to the right hand by means of cam 84 and lever 84^a, which turns the hook 77, centrally with the clamping spindle 62. The clamping spindle 62 is then retracted or lowered into the winding spindle 116, for a distance corresponding to the length of the spool by the lever 81, and its operating cam 83, permitting the wound and finished spools to drop. The stop 78 has a collar 114 surrounding the main spindle support 74 and with which the cam operated arm 81^a engages (Figs. 20, 21), the external surface of the main support constituting a guide for the stop. At the top of the winding spindle 116, is mounted a head 115, which furnishes a suitable base for the end of the spool, being placed at right angles to the axis of the winding spindle 116 and providing means for clamping the spool to the spindle for the operation of winding. To the winding spindle 116 is rigidly secured the angle gear 75, so that the head 115 revolves with the gear 75. There is a splined connection 75^a (Figs. 21 and 22^a) between the wind-

6

ing spindle 116 and the clamping spindle 62, with the bevel gear 75, so that the clamping spindle 62 has a free longitudinal movement relatively to the winding spindle 5 116, and can move downward when the stop 78 is depressed to its limit, but revolves when the gear 75 is revolved. The clamping rod 76, which extends through the winding spindle 116 and clamping spindle 10 62, being eccentric to the clamping spindle 62, at its upper end, is made concentric with the clamping spindle at its lower end, this being permitted on account of the length of the clamping rod 76. The distance between 15 the hook 77 and the point where it is connected to gear 79, is slightly greater than the length of the clamping spindle 62 (see Fig. 22^b), with the result that when the gear 79 is moved to its uppermost position 20 to engage rack 80, the hook 77 is moved out of a slot in the clamping spindle 62, so as to be capable of being revolved by the gear 79, relatively to the winding spindle 116, and clamping spindle 62. A spring 25 117, engaging a collar 118, bearing against a stop 118', fixed to the clamping spindle 62, tends to move the gear 79, and hook 77, downward relatively to the winding spindle 116 and clamping spindle 62, so as to hold 30 the hook 77 in clamping position when it is desired to clamp a spool.

In order to lessen the friction during the half revolution of the clamping hook 77 with the clamping spindle 62, I provide a 35 collar 119, against which the lower end of the spring 117 bears, and anti-friction balls 120, in a raceway between the collar and the gear 79. After the winding has been completed, the stop 78, as before stated, is 40 raised, permitting the hook 77 to be turned into normal position. The clamping spindle 62 then drops into the winding spindle to the level of the head 115, whereupon the wound and finished spools drop into a 45 conveyor trough 121, having a conveyer belt 122, driven by a suitable means, and are conveyed to the left hand end of the machine. The spring clamp arms 58, which have now 50 received empty spools, move and place them upon the spindle head 115, in a manner heretofore described. The cam 83, then acting through its lever 81, raises the stop 78, and returns the clamping spindle 62, through the hole in the spool, to normal position. The 55 cam 6 on the barring shaft thereupon releases the lever 7 so as to throw the belt shifter and shift the belt 10' from the cam operating pulley 8 to the fixed pulley 2' upon the driven shaft 2, whereupon the cam shaft 5 60 and the barring shaft 4 stop, and the main shaft 1, together with the flier shaft 2, begin to revolve. After the fliers 26 have made a few revolutions, a cam 123 (Figs. 8, 16, 17) loosely mounted upon the cam shaft 2

and driven from the main shaft by a 65 sprocket chain 124 on sprocket wheels 124^a—124^b engages an arm 125 of the shaft 100, which opens the clamps 97 which hold the ends of the thread, thereby releasing them. This temporary holding of the thread during the first few turns of the flier insures the proper starting of the wind. The wind then continues with the spindle frame C in one position for a while, after which the spindle frame is tilted by the cams 81 on the 75 main shaft, as before described, and the winding continues until the main shaft 1 has made one complete revolution, whereupon the trip 13 heretofore described is actuated by cam 12 to release the belt shifter 10, resulting in the shifting of the belt to the pulley 3 which operates the barring and main cam shafts, after which the finishing action takes place, as heretofore described.

In order to insure the quick stopping of the spindle shaft and of the barring mechanism, I provide two brakes, one consisting of a wheel 126 mounted upon the pulley shaft and engaged by a strap 127 connected to a weighted lever 128 (Figs. 2 and 3). 80 This weighted lever has an antifriction roll which is engaged by a cam 129 upon the belt shifter when the same is in the left hand position, as shown in Fig. 2. The upper part of the pulley 3 is provided with a brake 95 shoe 130 (Fig. 2) pivotally mounted, the same having an arm 131 which is engaged by a cam 132 upon the belt shifter when the belt shifter, as viewed in Fig. 2, is in the right hand position. These brakes act alternately 100 on the shaft 2 and pulley 3 and secure the prompt stopping of the parts after they have completed their functions. The braking action of the belt 127, however, is such as to be overcome by the action of the cam 105 23 while producing the three additional turns of the fliers above referred to. The thread for winding is contained on cops 133 of ordinary fashion, and is passed through suitable tensions 134 and thence through the 110 fliers 26 in the ordinary way.

When power is applied through the belt to the machine it will continue to operate automatically to place, wind, finish and remove spools so long as the horizontal chutes 115 are kept supplied with empty spools.

The apparatus as above described is the preferred embodiment of my invention, but as will be evident to those skilled in the art, it permits of various modifications without 120 departing from the spirit thereof or the scope of the appended claims.

What I claim is:

1. In a winding machine, the combination of a winding spindle, means for placing spools thereon one at a time, means extending from said spindle and movable relatively thereto for clamping said spools on said 125

- spindle, and a single source of power for actuating both of said means.
2. In a winding machine, the combination of a winding spindle, means for placing spools thereon one at a time, a clamping spindle extending from said winding spindle, means for separating said spools and clamping spindle from each other by a movement relatively to said winding spindle, and a single source of power for actuating both of said means.
3. In a winding machine, the combination of a winding spindle, means for placing spools thereon one at a time, means extending from said winding spindle and movable relatively thereto for clamping and unclamping said spools on said spindle, and a single source of power for actuating all of said means.
- 20 4. In a winding machine, the combination of a winding spindle, means for placing spools thereon one at a time, a clamping spindle, means for inserting and withdrawing said clamping spindle from said spools, and a single source of power for actuating both of said means.
5. In a winding machine, the combination of a winding spindle, means for placing spools thereon one at a time, means extending from said winding spindle for clamping said spools upon said spindle, means for withdrawing said spool clamping means from said spools, and a single source of power for actuating all of said means.
- 30 6. In a winding machine, the combination of a spindle, a hook member passing through said spindle and revoluble about an axis eccentric to the axis of said spindle, means for reciprocating said hook member and revolving it on its eccentric axis so as to clamp and unclamp a spool upon said spindle.
7. In a winding machine, the combination of a winding spindle, means for placing spools thereon one at a time, a slide for transferring spools to said placing means, a vertical chute in proximity to said slide, and a yoke in proximity to the upper end of said chute and to said slide for transferring spools from the upper part of said chute to said slide, and means for actuating said yoke.
- 45 8. In a winding machine, the combination of a winding spindle, means for feeding spools thereto one at a time, said feeding means comprising a chute, a reciprocating yoke having spool-receiving projections, a slide for receiving said spools from said yoke, means for reciprocating said slide, an oscillating clamping arm for receiving said spools from said slide, and means for oscillating said arm so as to place the spools on said spindle.
- 55 9. In a winding machine, the combination of a winding spindle, means for feeding spools thereto one at a time, said feeding means comprising a chute, a reciprocating yoke having spool-receiving projections, a slide for receiving said spools from said yoke, means for reciprocating said slide, an oscillating clamping arm for receiving said spools from said slide, and means for oscillating said arm so as to place the spools on said spindle.
- 10 10. In a winding machine, the combination of a winding spindle, means for feeding spools thereto one at a time, said feeding means comprising a chute, a reciprocating yoke having spool-receiving projections, a slide for receiving said spools from said yoke, means for reciprocating said slide, an oscillating clamping arm for receiving said spools from said slide, and means for oscillating said arm so as to place the spools on said spindle, and means for separating said spools and said spindle from one another.
- 15 11. In a winding machine, the combination of a series of winding spindles, a corresponding series of vertical chutes, a corresponding series of horizontal chutes, means for transferring spools from said horizontal chutes to said vertical chutes and forcing them upward in said vertical chutes, and means for transferring spools one at a time from the upper ends of said vertical chutes to said spindles.
- 20 12. In a winding machine, the combination of a hollow winding spindle, a clamping spindle longitudinally movable therein and also revoluble therewith, and means for withdrawing said clamping spindle from normal spool-holding position.
- 25 13. In a winding machine, the combination of a hollow winding spindle, a clamping spindle longitudinally movable therein and also revoluble therewith, means for withdrawing said clamping spindle from normal spool-holding position and returning it to normal spool-holding position, a clamping rod passing through said clamping spindle for holding said spool on said hollow spindle, and means for operating said clamping rod to hold and to release the spool.
- 30 14. In a winding machine, the combination of a winding spindle, a bearing for supporting the same, a clamping spindle, a hook member passing through said spindles and revoluble therewith, said hook being revoluble on an axis eccentric to the axis of said clamping spindle, means for causing said hook to protrude, and means for turning said hook about its eccentric axis from clamping position to non-clamping position, and vice versa.
- 35 15. In a winding machine, the combination of a spindle, a needle for finishing the

winding formed thereon, means for winding thread about said spindle, means for stopping the winding, means for moving the needle into proximity with the wound thread, means for causing the winding to be resumed so as to cause turns of the thread to pass over said needle, means for moving the needle to thread-receiving position and retracting said needle so as to withdraw it from beneath said turns, means for clamping said thread, means for severing said thread substantially as said needle is retracted, means for separating said spool from said spindle and placing on said spindle an unwound spool, means for causing said normal winding to resume, and means for releasing said thread clamp after said normal winding has been resumed.

16. In a winding machine, the combination of a series of winding spindles, a shaft having arms thereon for placing spools on said spindles, means for moving said shaft

so as to cause said arms to place the spools on said spindles, a retracting lever engaging 25 a projection on said shaft, and means for moving said lever quickly in arm-retracting direction and means for automatically feeding spools to said placing arms.

17. In a winding machine, the combination of a series of winding spindles, a shaft having arms thereon for placing spools on said spindles, means for moving said shaft so as to cause said arms to place the spools on said spindles, a retracting lever engaging 30 35 an arm on said shaft, means for moving said lever quickly in arm-retracting direction, and a slipping belt on said shaft normally tending to retract the same and cause it to complete its retracting movement after the quick action of said lever.

JOHN MACKIE.
